DEVICE FOR DRYING LIFTING GAS FOR AIRSHIPS

Filed Feb. 17, 1926

UNITED STATES PATENT OFFICE

ERNST BESCH, OF FRIEDRICHSHAFEN, GERMANY, ASSIGNOR TO LUFTSCHIFFBAU ZEPPELIN GESELLSCHAFT MIT BESCHRANKTER HAFTUNG, OF FRIEDRICHSHAFEN, GERMANY

DEVICE FOR DRYING LIFTING GAS FOR AIRSHIPS

Application filed February 17, 1926, Serial No. 88,973, and in Germany February 23, 1925.

My invention relates to a device for drying gas, especially gas used for inflating balloons, airships and the like, and to the method of inflating such lifting gas containers.

5 The gas intended for use in airships after its manufacture generally is stored under low pressure in large gasometers or compressed in special containers adapted to withstand high pressure. In most cases both kinds of storage 10 are utilized for inflating airships, especially those of large sizes.

The gas stored in gasometers generally has a considerable admixture of steam which reduces the lifting power of the gas. The gas 15 which was compressed does not exhibit this disadvantage. When inflating the gas cells of an airship large tubes are utilized for the purpose of avoiding great gas velocity. The compressed gas usually stored under a pressure 20 of 150 atmospheres is led into these tubes and passes through an expansion nozzle. In expanding the gas cools down and withdraws heat from the surrounding nozzle and the gas surrounding it.

25 According to my invention this cooling effect is utilized for the purpose of reducing the temperature of the gas which was stored in a gasometer thereby condensing part of the steam contained therein. To this end the expansion nozzle is situated inside of the large 30 tubes leading from the gasometer to the gas cells so that the highly compressed gas expanding through the nozzle withdraws heat from the surrounding gas coming from the 35 gasometer. The water condensed in this way may be caught in special devices arranged for this purpose.

It may be advisable to add a system of 40 cooling tubes behind the nozzle inside of the large tubes thereby increasing the cooling effect of the expanding gas on the surrounding gas. Also an expansion engine may be inserted in the pipes leading from the containers of the compressed gas to the expansion nozzle. In this expansion engine the gas 45 temperature will already be cooled down and besides mechanical energy may be derived therefrom.

Having given a general description of my 50 invention I now want to point it out more in

detail referring to the drawing which represents an example embodying my invention.

The figure is a longitudinal section through a part of the tubing leading from the gasometer to the gas cell showing the arrangement 55 for admixing compressed gas.

The wide tube 1 leads the low-pressure gas from a gasometer 11 in the direction of arrow 2. Compressed gas is led from a compression tank or container 12, into a tube 3 in the direction of arrow 4. It first passes through turbine 5 expanding therein and developing mechanical energy which may be used for any purpose. At the same time this gas cools down and then is led through tube 6 into tube 1, there passing through nozzle 7 and again expanding as it enters one end of a system of cooling coils 8 connected to the nozzle 7. At the other end of the coil the formerly compressed gas enters the tube 1 where it mixes with the low-pressure gas and is led in the direction of arrows 9 to the gas cell 13 that is to be inflated. A special device 10 is provided for the purpose of collecting the 70 water condensed from the low-pressure gas. 75

I do not want to be limited to the details described or shown in the drawing, as many variations will occur to those skilled in the art.

What I claim is:

1. The combination with a gasometer having a relatively large conduit attached thereto for conducting aircraft lifting gas under low pressure to a gas cell, of a high pressure aircraft lifting gas container, means extending from the container into the conduit for relieving the pressure in the gas from the high pressure container, and means for mixing the gas at relatively low pressure as it is conducted through the conduit toward the gas 90 cell.

2. The combination with a gasometer having a relatively large conduit attached thereto for conducting aircraft lifting gas under low pressure to a gas cell, of a container having aircraft lifting gas under relatively high pressure therein, means for conducting the gas from the container into the conduit, means for expanding the gas, and means for conducting the expanded gas into the gas 100 cell.

stream in the large conduit leading to the gas cell.

3. The combination with a gasometer having a relatively large conduit attached thereto for conducting aircraft lifting gas under low pressure to a gas cell, of a high pressure aircraft lifting gas container, an expanding means for the high pressure gas having a discharge port within the conduit and connected 10 to the container, and means for collecting water of condensation of the gas in the conduit.

4. The combination with a gasometer having a relatively large conduit attached thereto for conducting aircraft lifting gas under 15 low pressure to a gas cell, of a high pressure aircraft lifting gas container, a relatively narrow tube communicating with the container and with the interior of the conduit, an 20 expansion nozzle connected to the tube at the interior of the conduit for supplying gas under relatively low pressure into the stream of gas conducted from the gasometer through the conduit.

25 5. The combination with a gasometer having a relatively large conduit attached thereto for conducting aircraft lifting gas under low pressure to a gas cell, of a high pressure aircraft lifting gas container having a tube 30 connected thereto communicating with the interior of the conduit, a cooling coil of greater cross-sectional area than the tube, and an expansion nozzle connecting the tube to the cooling coil, said cooling coil opening into 35 the gas stream within the conduit leading from the gasometer to the gas cell.

6. The combination with a gasometer having a relatively large conduit attached thereto for conducting gas under low pressure to 40 a gas cell, of a high pressure gas container having a tube connected thereto, an expansion engine communicating with the tube, means extending from the engine into the interior of the conduit, an expansion nozzle 45 connected to the means inside the conduit, a cooling coil connected to the expansion nozzle for conducting gas at relatively low pressure into the conduit, and means for collecting the water of condensation within the 50 conduit.

7. The combination with a gasometer having a relatively large conduit attached thereto for conducting gas under low pressure to a gas cell, of a high pressure gas container 55 having a tube connected thereto, a turbine connected to the tube, a second tube of greater diameter than the first-mentioned tube connected to the turbine and extending into the conduit, a cooling coil of greater diameter 60 than the second-mentioned tube having a discharge port into the conduit, an expansion nozzle connecting said tubes, and means for collecting the water of condensation in the conduit.
